Primary Examiner—James Gandy*Assistant Examiner*—Stacia Sinuik*Attorney, Agent, or Firm*—Armstrong, Teasdale, Schlafly & Davis[57] **CLAIM**

The ornamental design for a traction tire, as shown and described.

DESCRIPTION

FIG. 1 is a front view, partially from the left, of a traction tire embodying the present invention; and, FIG. 2 is a front view, partially from the right, of the traction tire of FIG. 1.

The tread pattern is understood to be repeated uniformly throughout the circumference of the traction tire.
